US0D1030734S

(12) **United States Design Patent** (10) Patent No.: **US D1,030,734 S**
(45) Date of Patent: ** Jun. 11, 2024

(54) **HOLDER FOR DATA PROCESSING DEVICE
AND MOBILE TELEPHONE WITH
WIRELESS SPEAKER**

(71) Applicant: **LG Display Co., Ltd.**, Seoul (KR)

(72) Inventors: **Sunghyun Heo**, Paju-si (KR);
Sangbum Lee, Paju-si (KR); **Jongmoo Lee**, Paju-si (KR); **Kyuhong Han**, Paju-si (KR)

(73) Assignee: **LG DISPLAY CO., LTD.**, Seoul (KR)

(**) Term: **15 Years**

(21) Appl. No.: **35/516,740**

(22) Filed: **Mar. 25, 2022**

(80) **Hague Agreement Data**

Int. Filing Date: **Mar. 25, 2022**

Int. Reg. No.: **DM/221710**

Int. Reg. Date: **Mar. 25, 2022**

Int. Reg. Pub. Date: **Mar. 31, 2023**

(30) **Foreign Application Priority Data**
